SCISSORS

Lyman C. Blair, Houston, Tex.

Application April 21, 1941, Serial No. 389,667

12 Claims. (Cl. 30—248)

This invention relates to scissors and more particularly to "offset" scissors in which the blades of the two pivotal components are offset from the respectively associated handles in the direction of the axis of the pivot or pintle. The invention further relates to an improved scissors assembly including a novel form of pintle connection between the pivotal components. The improved pivotal connection, although especially suited for embodiment in "offset" scissors also may be used in scissors or shears of the more conventional kind.

As is now well known, the offsetting of scissors blades and handles enables the operator to cut more conveniently and accurately because the line of vision may coincide with the line of cutting without being obstructed by the operator's hand. Moreover, the scissors may be used without the operator's hand being held in a strained or uncomfortable position. The better vision and ease of operation are advantageous for nearly all, if not all kinds of cutting work but these advantages are of particular and sometimes crucial importance in surgical work in cavities.

An object of the present invention is to provide an improved "offset" scissors construction in which the parts are so assembled and related as to provide better and more permanent alignment of the cutting blades than has been possible with scissors heretofore known.

Another object is to provide an improved arrangement for holding the pivotal scissors components in assembly. A correlative object is to provide for easily adjusting or reconditioning the scissors to compensate for wear.

Other objects will be apparent from a reading of the following detailed description of one embodiment of the invention, the appended claims, and the accompanying drawing, in which:

Figure 1 is a plan view of a pair of offset scissors embodying the invention in one form;

Figure 2 is a section on the line 2—2 of Figure 1;

Figure 3 is an enlarged fragmentary vertical sectional view;

Figure 4 is a fragmentary sectional view on the line 4—4 of Figure 2; and

Figure 5 is a perspective view showing certain parts in separated relation.

As shown in the drawing the invention is embodied in "offset" scissors including pivotal components generally designated A and B.

The pivotal component A comprises a blade 1, a sleeve 2 formed integrally with the blade at one end of the sleeve, and a handle 3 formed in-

tegrally with the sleeve at its other end. The outside diameter of the sleeve is approximately equal to the maximum width of the blade, and the length of the sleeve is substantial, the exact length depending upon the amount of offset desired.

The component B comprises a blade 4, a hollow pintle 5 integral with the blade 4, and a handle 6 detachably connected to the pintle adjacent the outer end thereof. In the form shown, the detachable connection between the pintle 5 and handle 6 is provided by forming the pintle end portion which projects beyond the handle 3 with a pair of open end slots 7—7 adapted interlockingly to receive lugs 8—8 on the handle 6 when the handle bore 9 is passed over the pintle end portion.

The diameter of the pintle throughout its length is less than the opening within the sleeve 2 so that, in assembling the components A and B, the pintle 5 is simply passed up through the sleeve 2 until the blades 1 and 4 are in proper cutting contact, and the handle 6 is slipped on the projecting end of the pintle with the lugs 8—8 extending radially into the slots 7—7. The pintle is of sufficient length to include a journal portion having bearing within the sleeve 2 and a projecting portion adapted to receive the handle 6 and a retaining device adapted to maintain the components in properly assembled relation.

In its preferred form, the retaining device comprises a split washer or snap ring 10 which is slip-fitted over the pintle end and received in a circumferential groove 11 formed in the pintle end. The outermost wall of the groove provides a shoulder 12 under which the snap ring 10 extends and which prevents outward movement of the snap ring. The width of the groove longitudinally of the pintle is greater than the thickness of the snap ring so that there is clearance at 13 between the snap ring and the inner wall of the groove 11. Consequently the snap ring, which is rigid axially of the pintle, has bearing engagement directly with the shoulder 12 and the adjacent face of the nearer component B. The parts are so formed as to permit the snap ring to be moved in and out of the groove 11 when the components are assembled so that, when the parts become worn, the wear may be taken up or compensated for by removing the snap ring and replacing it with one of slightly greater thickness.

The construction disclosed herein provides for the accurate and permanent alignment of the cutting blades without the necessity of including heel extensions provided in some offset scissors

heretofore known. Elimination of the heel extensions lessens the danger of the scissors being accidentally caught in the work. The means for securing or retaining the pivotal components in assembled relation is simple and dependable, and is adapted to be easily adjusted to compensate for wear.

Although the illustrative construction shown herein embodies the invention in the now preferred form, it will be understood that changes may be made within the scope of the invention as defined in the claims.

I claim:

1. In scissors construction, the combination of a pair of pivotal scissors components; a pintle pivoting said components and having an end portion projecting axially beyond said components and a shoulder facing in a direction opposite the direction of projection of said end portion and toward said components, the shoulder being radially entirely within the circumference of the pintle; and a retaining member interposed between said shoulder and the adjacent face of the nearer of said components and engaging said nearer component immediately adjacent said pintle.

2. In scissors construction, the combination of a pair of pivotal scissors components; a pintle pivoting said components and having an end portion projecting axially beyond said components and a shoulder facing in a direction opposite the direction of projection of said end portion and toward said components, the shoulder being radially entirely within the circumference of the pintle; and a retaining member interposed between said shoulder and the adjacent face of the nearer of said components and engaging said nearer component immediately adjacent said pintle, said retaining member being rigid axially of said pintle.

3. In scissors construction, the combination of a pair of pivotal scissors components; a pintle pivoting said components and having an end portion projecting axially beyond said components and a shoulder facing in a direction opposite the direction of projection of said end portion and toward said components, the shoulder being radially entirely within the circumference of the pintle; and a snap ring slip-fitted around said projecting end portion and between said shoulder and the adjacent face of the nearer of said components.

4. In scissors construction, the combination of a pair of pivotal scissors components; a pintle pivoting said components and having an end portion projecting axially beyond said components and a shoulder facing in a direction opposite the direction of projection of said end portion and toward said components, the shoulder being radially entirely within the circumference of the pintle; and a snap ring surrounding said projecting end portion and being disposed between said shoulder and the adjacent face of the nearer of said components, said pintle and said nearer component being so formed as to permit said snap ring to be slipped in and out of operative position while said component and said pintle are in assembled relation.

5. Scissors construction as defined in claim 1 in which the pintle is formed integrally with the blade of one of the components.

6. Scissors construction as defined in claim 1 in which one of the components comprises a blade formed integrally with said pintle and a handle connected to the blade, and in which the

other of said components comprises a pintle-receiving sleeve formed integrally with a blade and a handle.

7. In scissors construction, the combination of a pair of pivotal scissors components; a pintle pivoting said components and having an end portion projecting axially beyond said components and a shoulder facing in a direction opposite the direction of projection of said end portion and toward said components, the shoulder being radially entirely within the circumference of the pintle; and a snap ring slip-fitted around said projecting end portion and between said shoulder and the adjacent face of the nearer of said components, said snap ring filling the axially extending space between said shoulder and the adjacent face of the nearer of said components and being removable for replacement by a similar but thicker snap ring to take up wear.

8. Scissors construction as defined in claim 3 in which the two pivoted components each includes a blade and a handle mutually offset axially of the pintle.

9. In scissors construction, the combination of a first pivotal component comprising a sleeve, a blade at one end of the sleeve and a handle at the other end of the sleeve; a second pivotal component comprising a blade, a pintle connected to said last named blade and having a portion extending through and journaled in said sleeve and an end portion projecting past the handle of said first component, and a handle on said pintle end portion outwardly beyond said first named handle, all portions of said pintle being of sufficiently small diameter to pass through said sleeve for assembly, said end portion of the pintle being formed with a circumferential groove; and a snap ring fitted in said groove and projecting radially from said pintle and overlying the handle of said second component.

10. In scissors construction; the combination of a first pivotal component comprising a sleeve, a blade at one end of the sleeve and a handle at the other end of the sleeve; a second pivotal component comprising a blade, a pintle connected to said last named blade and having a portion extending through and journaled in said sleeve and an end portion projecting past the handle of said first component, and a handle on said pintle end portion outwardly beyond said first named handle, all portions of said pintle being of sufficiently small diameter to pass through said sleeve for assembly, said end portion of the pintle being formed with a circumferential groove; and a snap ring fitted in said groove and projecting radially from said pintle and overlying and having bearing contact with the handle of said second component, said groove having a width longitudinally of the pintle in excess of the thickness of said snap ring whereby said snap ring may be replaced by a snap ring of greater thickness to take up wear.

11. Offset or "bayonet" shears comprising a bearing sleeve having a blade extending from one end thereof and a handle projecting diametrically oppositely with respect to said blade from the other end of said sleeve, the diameter of said sleeve approximating the width of said blade, a large diameter hollow pintle rockable in and projecting at its ends from said sleeve, a blade carried by one end of said pintle and engaging in shearing relation with the first mentioned blade, the other end of the pintle having a radial slot formed therein, a handle member having a bore therein for receiving the slotted end of the

pintle and a lug extending into said bore for connecting the pintle for movement with the bored handle member, and means for removably securing the bored handle member on the slotted pintle end.

12. Offset or "bayonet" shears comprising a bearing sleeve having a blade extending from one end thereof and a handle projecting diametrically oppositely with respect to said blade from the other end of said sleeve, the diameter of said sleeve approximating the width of said blade, a large diameter hollow pintle rockable in and projecting at its ends from said sleeve, a blade car-

ried by one end of said pintle and engaging in shearing relation with the first mentioned blade, the other end of the pintle having a radial slot formed therein, a handle member having a bore therein for receiving the slotted end of the pintle and a lug extending into said bore for connecting the pintle for movement with the bored handle member, said slotted pintle end having an annular groove therein, and a snap ring mountable in and removable from said groove and engaging the bored handle member for removably securing the assembly of the shears.

LYMAN C. BLAIR.
